UNITED STATES PATENT OFFICE

2,436,729

CONSTRUCTION OF INTERNAL-COMBUSTION ENGINES

Edward Philip Paxman, Colchester, England

Application June 26, 1944, Serial No. 542,174
In Great Britain March 10, 1943

3 Claims. (Cl. 123—195)

1

This invention relates to multi-cylinder internal combustion engines and more particularly to the Diesel type, and has for its object to provide improvements in the design of such engines in order to simplify and expedite manufacture and assembly.

In the production of engines of the kind above indicated it has been common practice to form each cylinder block as a single casting but owing to the necessity for providing supports for the cylinder liners, mounting for the cam shaft and accessory parts and water cooling spaces, the joint face between cylinder block and crank case is irregular and requires a number of separate and often complex and difficult operations to machine its co-operating surfaces. Further complex and accurate machining is necessary to secure exact alignment between various components often involving difficult and slow procedure.

In a prior Pat. No. 2,429,105, granted October 14, 1947, a mode of construction has been described designed to avoid the difficulties described in the preceding paragraph in the manufacture of internal combustion engines of the kind wherein two banks of cylinders are arranged in mutually inclined positions on a common crank case, and the present invention provides an extension of the said prior invention to the construction of vertical engines.

With a view to extending the utility of the prior invention the present invention provides for the unitary components therein described to be employed in engines of the vertical type, thereby enabling engines for different purposes to be simply and expeditiously constructed from standard units while the specialised machining and alignment work is reduced to the minimum.

According to the invention a multi-cylinder internal combustion engine of the vertical type is provided including a crank case having plane uninterrupted joint faces formed thereon, cylinder blocks adapted to be bolted in position thereon, a cam box assembly also adapted to be bolted in position in said crank case and cylinder head units having plane uninterrupted joint faces adapted to be seated upon and fixed to correspondingly formed faces on the cylinder blocks.

According to the preferred form of the invention an internal combustion engine of the type having a number of cylinders disposed vertically above a crank shaft is provided including a crank case constituted by a number of interconnected horizontal girders having thereon a central joint face and a second joint face at one side of said

2

central joint face, cylinder blocks adapted to be mounted on said central joint face, a cam box adapted to be mounted on the side joint face and cylinder head units adapted to be mounted on the cylinder blocks, said cylinder blocks, cam box and cylinder head units all being formed as sub-assemblies prior to the assembly of the engine and all joint faces being formed each with its component parts lying in a common plane.

Reference will now be made to the accompanying drawings which illustrate an example of a construction according to the invention, and in which:

Fig. 1 is a cross sectional elevation taken 15 through a six-cylinder engine,

Fig. 2 is a side elevation of a cylinder block for the engine shown in Fig. 1,

Fig. 3 is a sectional elevation of the cylinder block taken on the line C—C, Fig. 2,

Fig. 4 is a sectional plan of the cylinder block shown in Figs. 2 and 3,

Fig. 5 is a sectional plan of the cylinder head unit for the engine shown in Fig. 1, and

Fig. 6 is a cross sectional elevation of the cylinder head unit taken on the line D—D of Fig. 5.

In the construction illustrated, the engine is formed with cylinder blocks (shown in detail in Figs. 2 to 4) each comprising three cylinders shown in Fig. 2, an individual cylinder being indicated at 3 in Fig. 1. By dividing the cylinders into separate blocks in this manner, the weight to be shifted for each successive machining operation to be performed and the size of machine required are considerably less than under former practice.

The base of each cylinder block is formed by a number of surfaces all lying in one plane indicated at 4 in Fig. 1, which renders the machining of such surfaces to form the component parts of a common joint face adapted to co-operate with a similarly formed joint face on the crank case, a simple operation requiring no intermediate changes in position during the machining operation. The upper surfaces of each cylinder block also lie in one plane indicated at 5 in Fig. 1, so that a single machining operation forms them into the component parts of a common joint face on which seats the joint face of the cylinder head unit 6.

To enable the two adjacent cylinder blocks to be connected, each is formed with apertured lugs 1 and 2 at its ends (see Figs. 2 and 3) which lie side by side on assembly and are connected by bolts passed through the apertures 7. The lugs are formed at each end of the cylinder block 55 so that any block is capable of use for either

end of an engine and does not require to be specially formed. In the recesses between the cylinders, bosses 8 are formed through which pass bolts 9 whose lower ends engage recesses 10 formed in the upper part of a crank case 11 whereby the cylinder blocks as complete assemblies are secured in their operative positions upon the said crank case. Fig. 4 is a sectional plan of the cylinder block and shows it to be formed as a single casting with interconnected water jackets 12 having water supply connections 13 and 14. The cooling water circulates from the jackets 12 through ports 62 and passages 63 into the water spaces 64 of the cylinder head units 6. From these units the water leaves by water outlet manifolds 65 which may also be utilised to cool the exhaust manifold 66 and its branches. Figure 4 also shows the positions of the bosses 8 which, being disposed in the recesses between the individual cylinders 3, cause no projections beyond the main outer walls of the cylinder block.

The crank case 11 consists of a single casting, and its form comprises essentially four longitudinal girders indicated at 15, 16, 17 and 18 in Fig. 1. These girders are connected at intervals in the length of the crank case by a number of webs having substantially radial strengthening ribs 19, said webs lying in planes at right angles to the axis of the crank shaft 26 and being reinforced by additional ribs 21 at the base to take the forces due to the combustion in the cylinder and to the reciprocating and rotating masses of the pistons, rods, bearings and crank shaft. The said reinforcements include long bolts 22 which extend completely through the base of the crank case from side to side. The base of the crank case is recessed at 23 to receive intermediate bearing elements 24 which support the under side of the crank shaft and through which the bolts 22 also pass. The girders 15 and 16 at the top of the crank case are machined to form a joint face at 25 on which the joint faces 4 of the cylinder blocks seat, and the joint face 25 is formed with apertures 26 through which project the cylinder liners 27 and the connecting rods 28 of the pistons 29. The upper surface of the girder 16 is also formed with a joint face at 30 lying all in one plane and inclined downwardly and outwardly from the central joint face 25.

In engines of the general character to which the present invention applies it has been the common practice to form a cam shaft housing integral with the main casing or casting. This practice not only possesses the disadvantage that a heavy and unwieldy casting is necessary, but it provides complexities in machining and assembly which add greatly to the time occupied in construction and assembly and necessitates a large proportion of skilled labour to carry out the operations necessary.

The arrangement above described whereby a joint face 30 is formed at one side of the cylinders provides a clear surface upon the crank case which is utilised for the disposition of a cam box 31 which extends completely along the top of the crank case and at one side thereof. This cam box, which is constructed and arranged preferably as described in the prior Patent No. 2,429,106, granted October 14, 1947, contains the cam shaft and rockers, and mounted upon its cover are the fuel pumps, timing gear and governors. This assembly after completion independently is placed in position upon the joint face 30 on the crank case, and is held in position by studs 32 which pass through the cover 33 of the cam box and

cam shaft bearings intermediate with studs which serve to retain the cover in place. This cover with the components mounted upon it can be removed to allow complete access to be obtained to the cam shaft without disturbing other parts of the engine. The arrangement permits of an overhang of the cam box at one end of the engine and it only needs aligning at one end where the timing gear is situated. The above described disposition of the cam box and the parts carried by it is facilitated by the arrangement of the cylinder blocks 3, whose walls are without substantial projections, the heads of the bolts 9 for fixing the cylinder blocks to the crank case being conveniently arranged within recesses as already described.

To enable the crank case to be formed as above described, specific relative proportions between the height of the crank case at its outer sides and of the individual cylinders are necessary. For this purpose the height of each cylinder 3 is reduced only to such an extent that the water cooling space 12 extending substantially to the point of junction with the crank case provides water cooling for the piston pressure rings at the bottom of the piston stroke. The reduction of cylinder length involves the use of the cylinder liner 27 which projects a certain distance into the crank case as shown in Fig. 1, and which may be reinforced near its outer end, for example, by a clamping ring 34 to prevent damage to the liner 27 if struck by the connecting rod 28 during assembly or dismantling operations.

To enable connecting rods and pistons to be removed when necessary the sides of the crank case are provided with openings normally covered by doors 35 and the vertical height of these openings, which must be sufficient to enable a piston and connecting rod to be inserted or withdrawn, determines the minimum height between the upper and lower girder components 15 and 17 or 16 and 18 at each side of the crank case and the positions of them.

Each cylinder block is provided with a cylinder head unit 6 which is formed independently as a sub-assembly complete with valves, valve-actuating gear, air cleaners, combustion chambers, injectors and other accessories in readiness for attachment to the cylinder block by seating upon the joint face 5. Fig. 5 shows a plan of one of the cylinder head units and includes bolts 36 by which this unit is secured in position on the cylinder block, these bolts engaging screw-threaded sockets formed in the top face of the cylinder block. Two of these bolts are also shown in elevation in Fig. 6. Fig. 5 also shows the air inlets 37, inlet valve spaces 38, combustion chamber 39, injector socket 40, exhaust valve spaces 41 and exhaust passages 42. The cylinder head unit is further illustrated in Fig. 1 which includes the air cleaners 43, one of the exhaust valves 44 and a passage 45 through which passes one of the valve actuating push rods 70 operated from the cam box 31. At 46 is one of the tubular sockets shown also in Fig. 6 through which pass the securing bolts 36.

The engine assembly is completed by a valve cover unit 47 which contains the valve rockers 48 and their accessory parts and has a lower joint face indicated at 33a, Fig. 1, the surfaces of which lie all in one plane and which is adapted to seat on a corresponding joint face formed on the upper part of the cylinder head unit 6.

A further simplification in manufacture is

effected by avoiding the necessity for accurate alignment between the apertures in the cam box 31 and the cylinder head unit 6 through which pass the push rods 70. These apertures are made sufficiently large to allow free passage and angular displacement of the push rods, and each pair of apertures in the cam box and cylinder head respectively is connected by a flexible sleeve 49 constructed according to prior Pat. No. 2,397,882, granted April 2, 1946, and adapted to be sprung into position after the main components of the engine have been assembled.

Engines constructed as above described possess the advantage that they can be manufactured with the minimum of difficulty. The crank case 11, which is the largest component, can be machined to form the joint faces and bored to receive the crank shaft bearings by straight line operations which do not involve any changes in position of the crank case during machining which would require heavy machinery. The remaining components, namely, the cylinder blocks, cylinder head units and valve cover units are relatively small, and consequently easy to manipulate, but the reduction in the number of consecutive machining operations due to the employment of joint faces whose components lie all in one plane, and the elimination of aligning operations requiring skilled labour on assembly, greatly reduce the time occupied in the completion of an engine.

In assembling an engine as above described many of the component units employed, such as cylinder blocks, cylinder head units and cam box, can be of the same design as those described in said prior Pat. No. 2,429,105.

I claim:

1. An internal combustion engine of the type having a row of cylinders disposed vertically above a crank shaft, comprising a crank case constituted by a plurality of interconnected longitudinal girders having thereon a joint face situated centrally of the width of the crank case and lying in a horizontal plane and a second joint face at one side of said centrally situated joint face and lying in an inclined plane,

5 cylinder blocks adapted to be mounted on said centrally situated joint face, a cam box adapted to be mounted on said second joint face, and cylinder head units adapted to be mounted on 10 the cylinder blocks, said cylinder blocks, cam box and cylinder head units all being formed as sub-assemblies prior to the assembly of the engine, and all joint faces between the crank case, cylinder blocks and cylinder head units 15 being formed each with its component parts lying in a common horizontal plane.

15 2. An internal combustion engine as defined in claim 1, including valve cover units adapted to be mounted on the respective cylinder head 20 units and having joint faces each formed with its component parts lying in a common horizontal plane, said cylinder blocks, cylinder head units and valve cover units comprising sub-assemblies superimposed one upon another and 25 on said horizontal centrally situated joint face on said crank case.

25 3. An internal combustion engine as defined in claim 1, wherein said girders comprise a pair of members extending along the upper portion 30 of said crank case, and said centrally situated joint face is formed on the upper surfaces of said girder members and said second joint face is formed at the outer side of one of said girder members.

30 EDWARD PHILIP PAXMAN.
